TOY PURSUIT CAR

Louis Marx, New York, N. Y.

REISSUED

Application October 11, 1935, Serial No. 44,484

12 Claims. (Cl. 46—112)

This invention relates to toys, and more particularly to a toy simulating an automobile or like vehicle carrying a person sighting and firing a gun during the operation of the automobile.

5 The primary object of my invention is to provide a toy simulating a pursuit car such as is used by police, Federal agents or the like. A more particular object is to provide such a toy with a simulated operator sighting and firing a machine gun from the pursuit car during its operation. Still further objects are to enhance the 10 realism of the toy in operation by producing a shower of sparks at the gun and by producing a succession of percussive sounds, thereby imitating the operation of the gun. Still another object of my invention resides in the provision of a single driving motor for simultaneously propelling the vehicle and operating the sparking and noise-making mechanisms of the gun.

15 A further object of my invention is to devise a simplified and economical construction for the toy. In this connection I may point out that the gun is necessarily small in dimension if kept within reasonable dimensional proportion to the vehicle. This makes it difficult if not impossible to localize the sparking mechanism directly within the gun body. In accordance with my invention the gun body is made small, but is left open at the bottom, and a spark-producing wheel is located beneath the gun and concealed by the 20 automobile body. The flint and friction wheel are so relatively located as to throw a shower of sparks forwardly and upwardly at the open bottom portion of the gun.

25 To the accomplishment of the foregoing and other objects which will hereinafter appear, my invention consists in the toy automobile and machine gun elements and their relation one to the other as are hereinafter more particularly described in the specification and sought to be 25 defined in the claims. The specification is accompanied by a drawing in which:

30 Fig. 1 is a side elevation of a toy embodying features of my invention;

35 Fig. 2 is a horizontal section taken in the plane of the line 2—2 of Fig. 1;

40 Fig. 3 is an enlarged section taken in the plane of the line 3—3 of Fig. 2; and

45 Fig. 4 shows the noise-making mechanism in elevation as viewed at the line 4—4 in Fig. 2.

50 Referring to the drawing, the toy of my invention comprises a simulated vehicle preferably in the form of a toy automobile generally designated A. Within the automobile there is placed the figure of an operator O holding and sighting

a machine gun G through the open windshield of the automobile. The firing of the gun is imitated by sparking mechanism generally designated S, the noise-making mechanism generally designated N. The toy is operated by a motor M which preferably drives the automobile, the 5 sparking mechanism and the noise-producing mechanism.

Considering the arrangement in greater detail, the toy automobile is made of sheet metal parts 10 simulating a chassis 12 surmounted by a radiator 14, a hood 16 and a coupe type body 18. The chassis 12 carries a front axle 20 bearing freely rotatable front wheels 22, and a rear axle 24 to which are secured rear or driving wheels 15 26. The chassis may be fitted with customary front and rear bumpers and mudguards.

The body 18 is cut away at the sides to form 20 side windows 28 and is also cut away at the front to form a windshield opening 30. It may also be cut away at the back to form a rear window opening 32. The operator O holding the gun G 25 may of course be seen through these windows.

The operator O and machine gun simulation G are 30 preferably formed integrally in an inexpensive manner by using two oppositely convexed sheet metal sides 34 and 36 (Fig. 2) which are fitted together in edge to edge relation and secured by appropriate connections such as the bent tongue connections 38 and the tongue and slot connections 40 visible in Fig. 2. The configuration of the sheet metal sides is such that the operator appears to hold the machine gun in proper position, and the dimension of the assembly is such that when the bottom of the figure 35 is placed on the floor or chassis plate of the automobile, the barrel of the gun G passes through the windshield opening 30 just above the inwardly flanged lower edge of the windshield opening thereof. The operator is secured to the 40 chassis plate by appropriate tongue and slot connections indicated at 42.

While the sides 34 and 36 are contiguous at their edges around most of the combined figure, these sides are left straight and open over a substantial portion of the bottom of the gun. In the specific example here illustrated the sides are closed at the muzzle portion 44, but are open beginning at the point 46 (Fig. 3). Beneath and partially housed by the breech portion of the 50 gun is a friction wheel 48 forming part of the sparking mechanism. This wheel is mounted on a shaft 50 journalled in a special frame 52 which extends downwardly to the bottom of the vehicle, where it is secured by appropriate tongue and 55

slot connections. The frame 52 is channel-shaped and the connecting face 54 thereof is preferably disposed rearwardly, thus constituting a forward bearing for a longitudinally disposed 5 downwardly sloping shaft 56. The lower end of shaft 56 is journalled in a bearing lug 58 struck from the side wall 60 of motor frame 62. The rear axle 24 of the vehicle carries a crown gear 64 meshing with a pinion 66 mounted on shaft 56 10 which in turn carries at its forward end a crown gear 68 meshing with a pinion 70 mounted on shaft 50. Rotation of axle 24 thus imparts rotation to the sparking wheel S, and the gearing is so arranged that the sparking wheel rotates in a 15 counter-clockwise direction as viewed in the drawing.

The sparking mechanism is completed by a suitable pyrophoric element 72 which for convenience may be referred to as a flint. This element is mounted at the trailing end of a strip of sheet metal 74, the forward end 76 of which is bent upwardly through a slot 78 at the top of the gun and then bent forwardly and downwardly as indicated by the change from the 25 broken line to the solid line position in Fig. 3. Holder 74 is received loosely within the gun body and within slot 78. This permits the same to self-adjustably rest on the friction wheel with a light gravitational contact which on the one 30 hand is adequate to produce a shower of sparks, but on the other hand, does not result in excessive friction or rapid wearing away of the flint. The flint and sparking wheel are so relatively 35 positioned that the resulting shower of sparks is thrown forwardly and upwardly at the open bottom portion of the gun, thus tending to throw the sparks into and through the muzzle of the gun.

It will be understood, however, that any 40 discharge of sparks at or immediately adjacent the muzzle is sufficient to produce the desired illusion, for the toy is for the most part viewed from above. I may also point out that the disposition of the sparking wheel here made is a 45 fortunate one in that the wheel is concealed without necessitating a special housing therefor because of its disposition immediately behind and below the front part 80 of the automobile body immediately below the windshield opening 38. 50 Although the wall 80 taken together with the machine gun body effectively conceals the sparking mechanism, there is no obstruction of the desired shower of sparks. Although the flint wears slowly it may be readily replaced if completely 55 worn out by bending the tip 76 of the flint holder upwardly to the broken line position shown in Fig. 3, whereupon the forward end of the holder may be dropped downwardly through the open bottom portion of the gun and the entire holder 60 drawn forwardly from the gun through the windshield opening. This represents an important additional advantage of using the open bottom construction for the gun, and it is therefore recommended that the open part of the gun be 65 carried forwardly to a point located approximately beneath the slot 78.

The noise-making mechanism N comprises 70 simply a hammer or clatter plate in the form of a leaf spring 82, the forward end of which is riveted beneath the chassis plate 12 by a suitable eyelet 84, while the rear end is bent to form a hammer portion 86 and a cam follower portion 88. The latter cooperates with a suitable cam 90 mounted on the rear axle 24 of the vehicle. 75 A multiple-toothed cam may be employed if pre-

ferred. The movement of spring 82 is guided by a pair of tongues 92 struck downwardly from the chassis plate on opposite sides of the spring. When the vehicle is propelled, rotation of the axle causes a clatter or series of percussive 5 sounds which is realistic in accompaniment with the sparking at the muzzle of the gun.

The motor M may be of conventional type and probably requires no detailed description. As here illustrated it comprises a main spring 94, 10 the inner end of which is secured to a square winding stem 96 and the outer end of which is anchored on the motor frame at 98. The end of stem 96 may be bent to form a suitable key, or as here illustrated, may be terminated without 15 a key, but projecting from the side of the vehicle to receive a suitable key, which has been omitted from the drawing. Stem 96 carries a main driving gear 100 which is driven through a suitable clutch or ratcheting device 102. Gear 20 100 meshes with a pinion 104 which in turn rotates a gear 106 meshing with a pinion 108 fixed on the rear axle 24 of the vehicle. The motor thus serves to drive the vehicle, the sparking mechanism and the noise-making mechanism. 25 A brake 110 is provided to stop the operation of the toy when desired. In the form illustrated, this brake is pivoted on one of the rear mudguards at 112, and is bent inwardly to form the brake shoe 114 movable into engagement with 30 the rubber tread of one of the rear wheels 26. The direction of rotation of the wheel is such as to tend to tighten the brake pressure once the brake has been set.

It is believed that the mode of constructing 35 and using, as well as the many advantages of my toy pursuit car, will be apparent from the foregoing detailed description thereof. The toy is realistic in operation because the normal operating noise augmented by the special noise- 40 making element combines with the spark ejection at the muzzle of the gun to produce an effect which is surprisingly heightened by the mobility and movement of the entire toy during the simulated firing of the gun. The toy is 45 comparatively economical to produce because a single driving motor is used for propelling all of the elements of the toy. The simulation of the operator and gun is simplified by forming both in a single unit made up of only two sheet 50 metal sides, and even these sides may if desired be made of a single piece of sheet metal folded at the back edge of the figure. The gun is properly proportioned to the vehicle, and although this results in necessarily making the gun very 55 small in dimension, it is nevertheless provided with a sparking wheel and flint of full size and these parts are so supported as not to require the use of delicate or miniature parts. Despite this fact the sparking mechanism is substantially 60 concealed, and the flint and flint holder are readily removable for replacement.

The gun is aimed through the front windshield because the toy is simulatedly a pursuit car, but it will be understood that it may be constructed with the gun pointed through a side or rear window instead of through the windshield, and that in this respect the windshield opening is generically a window opening like the side and rear windows. 65

It will therefore be understood that while I have shown and described my invention in a preferred form, many changes and modifications may be made in the structure disclosed without departing from the spirit of the invention de- 70 75

fined in the following claims. In referring there-
in to the operator as formed of two sides I do
not mean to exclude the preferred construction
here illustrated in which the two sides are folded
5 from a single piece of sheet metal.

I claim:

1. A toy comprising a wheeled toy automobile
the body of which is provided with a window opening,
a simulated machine gun the barrel of which
10 projects through the window opening, a friction
wheel rotatably mounted inside said auto-
mobile body beneath and partially housed by the
gun, said wheel being so disposed as to be sub-
stantially concealed by the automobile and ma-
chine gun bodies, a flint engaging said wheel, and
15 means gearing said wheel to the automobile
wheels.

2. A toy comprising a wheeled vehicle the body
of which is provided with a window opening, a
20 simulated machine gun the barrel of which pro-
jects through the window opening, a friction
wheel rotatably mounted inside said vehicle body
beneath and partially housed by the gun, said
wheel being so disposed as to be substantially
25 concealed by the vehicle and machine gun bodies,
a flint engaging said wheel, noise-making mech-
anism including a vibratile noise-making element
and a rotatable cam for actuating the same, and
a motor geared to the aforesaid friction wheel
30 and cam.

3. A toy simulating a pursuit car used by po-
lice, Federal agents or the like, said toy comprising
a toy automobile, the body of which is pro-
vided with a window opening, a simulated ma-
chine gun the barrel of which projects through
35 the window opening, a friction wheel rotatably
mounted inside said automobile body beneath and
partially housed by the gun, said wheel being so
disposed as to be substantially concealed by the
automobile and machine gun bodies, a flint en-
gaging said wheel, noise-making mechanism in-
cluding a vibratile noise-making element and a
rotatable cam for actuating the same, and a mo-
tor geared to the wheels of the vehicle and to the
45 aforesaid friction wheel and cam.

4. A toy simulating a pursuit car used by po-
lice, Federal agents or the like, said toy comprising
a toy automobile, the body of which is pro-
vided with a windshield opening, a simulated ma-
chine gun the barrel of which projects through
50 the windshield opening, said machine gun being
formed of sheet metal bent to inverted trough
shape and open over a substantial part of the
bottom thereof, a friction wheel rotatably
mounted inside said automobile body beneath and
55 partially housed by the open portion of the ma-
chine gun, said wheel being so disposed as to be
substantially concealed by the parts of the auto-
mobile and machine gun bodies, a flint carried
60 by a flint holder loosely pivoted through a slot
at the top of the machine gun body, said flint
holder being so disposed as to throw a shower of
sparks forwardly and upwardly along the open
bottom portion of the machine gun, and means
65 to drive the aforesaid friction wheel.

5. A toy simulating a pursuit car used by po-
lice, Federal agents or the like, said toy comprising
a toy automobile, the body of which is pro-
vided with a windshield opening, a simulated ma-
chine gun the barrel of which projects through
70 the windshield opening, said machine gun being
formed of sheet metal bent to inverted trough
shape and open over a substantial part of the
bottom thereof, a friction wheel rotatably mount-
75 ed inside said automobile body beneath the open

portion of the gun, said wheel being so disposed
as to be substantially concealed by the parts of
the automobile and machine gun bodies, a flint
carried by a flint holder loosely pivoted through a
slot at the top of the machine gun body, said flint
holder being so disposed as to throw a shower of
sparks forwardly and upwardly along the open
bottom portion of the machine gun, noise-making
mechanism including a vibratile noise-making
element and a rotatable cam for actuating the
same, and a motor geared to the wheels of the
automobile and to the aforesaid friction wheel
and cam.

6. A toy simulating a man holding and sight-
ing a machine gun, said toy comprising two sheet
15 metal sides oppositely convexed and secured to-
gether by appropriate connections, said sheet
metal sides having a configuration simulating the
man holding the machine gun in proper position,
said sides fitting together in edge to edge rela-
20 tion to form a closed body except beneath the
barrel and breech portions of the machine gun
whereat the sides are left open in spaced rela-
tion, a friction wheel rotatably mounted at the
open breech portion of the machine gun, and a
25 flint engaging said wheel.

7. A toy simulating a man holding and sight-
ing a machine gun, said toy comprising two sheet
metal sides oppositely convexed and secured to-
gether, said sheet metal sides having a configura-
30 tion simulating the man holding the machine
gun in proper position, said sides fitting together
in edge to edge relation to form a closed body
except beneath the barrel and breech portions of
the machine gun whereat the sides are left open
35 in spaced relation, a friction wheel rotatably
mounted at the open breech portion of the ma-
chine gun, a flint fixed at the trailing end of an
elongated sheet metal holder the forward end of
which is bent upwardly through a slot at the top
40 of the machine gun simulation, said holder being
freely movable in said slot and being removable
through the open bottom of the gun for replace-
ment.

8. A toy comprising a toy automobile the body
45 of which is provided with a windshield opening
and window openings, a simulated man holding
and sighting a machine gun through the wind-
shield opening, said simulation comprising two
50 sides oppositely convexed and secured together,
said sides having a configuration simulating the
man holding the machine gun in proper position,
the edges of said sides fitting together in edge to
edge relation to form a closed body except be-
55 neath the barrel and breech portions of the ma-
chine gun whereat the sides are left open in
spaced relation, a friction wheel rotatably mount-
ed in the open breech portion of the machine
gun and concealed thereby and by the auto-
60 mobile body, a flint engaging said wheel, and means
gearing the wheels of the automobile to the afore-
said friction wheel.

9. A toy simulating a pursuit car used by police,
Federal agents or the like, said toy comprising a
65 toy automobile, the body of which is provided with
a windshield opening and window openings, a simu-
lated man holding and sighting a machine
gun through the windshield opening, said simu-
lation comprising two sheet metal sides oppo-
70 sitely convexed and secured together, said sides hav-
ing a configuration simulating the man holding
the machine gun in proper position, the edges
of said sides fitting together in edge to edge rela-
tion to form a closed body except beneath the
75 barrel and breech portions of the machine gun

- whereat the sides are left open in spaced relation, a friction wheel rotatably mounted in the open breech portion of the machine gun and concealed thereby and by the automobile body, a flint engaging said wheel, noise-making mechanism including a vibratile noise-making element and a rotatable cam for actuating the same, and means to drive the aforesaid friction wheel and cam.
10. A toy simulating a pursuit car used by police, Federal agents or the like, said toy comprising a toy automobile, the body of which is provided with a windshield opening and window openings, a simulated man holding and sighting a machine gun through the windshield opening, said simulation comprising two sheet metal sides oppositely convexed and secured together, said sides having a configuration simulating the man holding the machine gun in proper position, the edges of said sides fitting together in edge to edge relation to form a closed body except beneath the barrel and breech portions of the machine gun, whereat the sides are left open in spaced relation, a friction wheel rotatably mounted in the open breech portion of the machine gun and concealed thereby and by the automobile body, a flint engaging said wheel, noise-making mechanism including a vibratile noise-making element and a rotatable cam for actuating the same, and a motor geared to the wheels of the vehicle and to the aforesaid friction wheel and cam.
11. A toy simulating a pursuit car used by police, Federal agents or the like, said toy comprising a toy automobile, the body of which is provided with a windshield opening and window openings, a simulated man holding and sighting a machine gun through the windshield opening, said simulation comprising two sheet metal sides oppositely convexed and secured together, said sides having a configuration simulating the man holding the machine gun in proper position, the edges of said sides fitting together in edge to edge relation to form a closed body except beneath the barrel and breech portions of the machine gun whereat the sides are left open in spaced relation, a friction wheel rotatably mounted in the open breech portion of the machine gun and concealed thereby and by the automobile body, a flint fixed at the trailing end of an elongated sheet metal holder the forward end of which is bent upwardly through a slot at the top of the machine gun simulation, said holder being freely movable in said slot and being removable through the open bottom of the gun for replacement, the flint and friction wheel being so disposed as to throw a shower of sparks forwardly at the open bottom portion of the gun simulation, and means to drive the friction wheel.
12. A toy simulating a pursuit car used by police, Federal agents or the like, said toy comprising a toy automobile, the body of which is provided with a windshield opening and window openings, a simulated man holding and sighting a machine gun through the windshield opening, said simulation comprising two sheet metal sides oppositely convexed and secured together, said sides having a configuration simulating the man holding the machine gun in proper position, the edges of said sides fitting together in edge to edge relation to form a closed body except beneath the barrel and breech portions of the machine gun whereat the sides are left open in spaced relation, a friction wheel rotatably mounted in the open breech portion of the machine gun and concealed thereby and by the automobile body, a flint fixed at the trailing end of an elongated sheet metal holder the forward end of which is bent upwardly through a slot at the top of the machine gun simulation, said holder being freely movable in said slot and being removable from the gun for replacement, the flint and friction wheel being so disposed as to throw a shower of sparks forwardly at the open bottom portion of the gun simulation, noise-making mechanism including a vibratile noise-making element and a rotatable cam for actuating the same, and a motor geared to the wheels of the automobile and to the aforesaid friction wheel and cam.

LOUIS MARX. 45
